UNITED STATES PATENT OFFICE.

ISOM J. ROSS, OF WAYNESVILLE, INDIANA.

BAND-CUTTER AND FEEDER FOR THRESHING-MACHINES.

SPECIFICATION forming part of Letters Patent No. 699,243, dated May 6, 1902.

Application filed August 2, 1900. Serial No. 25,668. (No model.)

To all whom it may concern:

Be it known that I, ISOM J. ROSS, a citizen of the United States, residing at Waynesville, Bartholomew county, State of Indiana, have 5 invented a new and useful Threshing-Machine Band-Cutter and Feeder, of which the following is a specification.

My invention is an improved band-cutter and feeder for threshing-machines; and it consists in the peculiar construction and combination of devices hereinafter fully set forth and claimed.

In the accompanying drawings, Figure 1 is a perspective view of a band-cutter and feeder constructed in accordance with my invention, showing the same disposed in operative relation to a threshing-machine. Fig. 2 is a vertical longitudinal sectional view of the same. Fig. 3 is a detail perspective view of the revolvable band-cutting and feeding cylinder. Fig. 4 is a detail sectional view of the same. Fig. 5 is a top plan view with a portion of the cover removed to disclose the band-cutting and feeding cylinder. Fig. 6 is a vertical longitudinal sectional view taken on the line *a a* of Fig. 5, showing the hinged section of the feed-pan open and lowered, the cross-bar which supports the same being removed. Fig. 7 is a detail transverse section taken on the 25 line *b b* of Fig. 5, showing the hinged section of the feed-pan closed and the cross-bar in position to support the same. Fig. 8 is a perspective view of the detachable cross-bar, that supports the hinged inner section of the grain- 35 pan.

In the embodiment of my invention I provide an oblong frame 1, which comprises the side bars 2 and cross-bars 3 3'. The inner end of the frame 1 is supported on the frame *a* of 40 a threshing-machine at the feed end of the latter, the said frame 1 being secured on said frame *a* by means of straps 4 and suitable bolts 5, as shown. Any other suitable means may, however, be employed for this purpose. 45 A cover 6 extends transversely over the inner portion of the frame 1 and is supported at a suitable distance above the same, as shown. Suitable bearings 7 are secured on the sides of the frame 1 under and near the outer end 50 of the cover 6. In these bearings is journalled the shaft 8 of a revolvable band-cutting and

feeding cylinder 9, the construction of which is hereinafter fully described. The sides 2 of frame 1 at the outer end of the latter have their upper edges inclined, as at 10, the said 55 inclines forming guideways on which are disposed the guide-bars 11 of a feed-pan 12. The said feed-pan has a hopper 13 at its outer end of suitable form, here shown as oblong. In the said hopper is a longitudinally-disposed 60 central partition-board 14, which divides the hopper into two longitudinal compartments 15, the inner lower ends of which are open. The hopper is about one-half the length of the feed-pan, and the bottom of the latter is 65 inclined and maintained in an inclined position by the guide-bars 11, which rest on the inclined guideways 10 of frame 1. The inner portion of the inclined feed-pan is formed by the section 16, which is hinged on its 70 under side, as at 17, to the outer portion of the feed-pan on which the hopper is located. The said hinged section 16 of the feed-pan is adapted to be opened downwardly, as indicated in dotted lines in Figs. 1 and 2, 75 to admit access to the threshing mechanism. When the said hinge-section 16 of the feed-pan is raised to its normal operative position, the same is disposed in the same plane as the outer portion of the feed-pan, as shown in 80 Fig. 2. A cross-bar 18 is removably secured to the threshing-machine frame *a* by turn-buttons 19 or other suitable devices, and said removable cross-bar when the hinge inner section of the feed-pan is raised to operative 85 position bears under the same, and hence maintains the same in operative position, as shown. A plate 18^a on said cross-bar bears on the lower side of the feed-opening of the threshing-machine and under the inner end 90 of the hinged section of the feed-pan. (Shown in Fig. 2.)

A shaft 20 is journaled in bearings 21 on the cover 6. Said shaft is provided at its ends on opposite sides of frame 1 with eccentrics 22. A power-pulley 23 is also secured to said shaft. Eccentric-rods 24 are connected to the sides of the outer portion of the feed-pan, as at 25, and are provided at their inner ends with eccentric-straps 26, in which 100 the eccentrics operate. Hence when the shaft 20 is rotated reciprocating motion is im-

parted to the feed-pan and hopper, as will be understood, the said reciprocating motion of the feed-pan, together with the inclined position thereof, causing the bundles of grain 5 to be fed from the hopper to the threshing mechanism, as will be understood. The revoluble band-cutting and feeding cylinder being disposed transversely over the feed-pan it follows that the same is disposed in the 10 path of the bundles, the latter passing under said revoluble cylinder and the bands thereof of being cut thereby, the said cylinder also assisting in feeding the grain to the threshing mechanism. The vertical longitudinal 15 partition-board 14 in the hopper coacts with the sides thereof in longitudinally disposing the bundles of grain thrown into the hopper, and hence causes the same to be fed lengthwise to the band-cutting and feeding cylinder 20 and to the threshing mechanism. The shaft 8 of said band-cutting and feeding cylinder is provided at one end with a pulley 27, (shown in dotted lines in Figs. 1 and 2,) which pulley is connected to the pulley 23 by an 25 endless belt 28. Thereby power is conveyed from the cylinder-shaft to the shaft 20. Said cylinder-shaft is further provided with a power-pulley 29, which may be driven by an endless belt (not shown) from one of the 30 power-shafts of the threshing-machine.

The band-cutting and feeding cylinder comprises a pair of circular heads 30, which are keyed on the shaft 8, and a plurality of bars 31, which connect the said heads together.

35 In the form of my invention here shown I employ three of the bars 31. Each of the same is formed of angle-iron. The ends of the bars 31 are outturned and riveted or bolted to the heads 30, as at 32. The said bars 31 by contact with the grain and the circular movement thereof serve to feed the grain to the threshing-machine, and said bars also support and carry the band-cutting knives 33, which are riveted or bolted on said bars, as 40 at 34. Each of the band-cutting knives is substantially of the form here shown and is formed with an integral foot 35. The said feet of said knives form bearing-surfaces for the latter, as will be understood.

45 50 My improved band-cutter and feeder may be readily attached to and detached from a threshing-machine by means of the straps 4.

Having thus described my invention, I claim—

1. A band-cutting and feeding attachment 55 for threshing-machines comprising a frame having means to detachably secure it to the feed end of a threshing-machine, the sides of the said frame having their upper edges inclined, an inclined reciprocating feed-pan 6c having guide-bars 11 on its sides, said guide-bars bearing on the inclined upper edges of the sides of the frame, whereby said feed-pan is guided in a right line and supported by said frame, the latter having a cover over the inner portion of said feed-pan, and said feed-pan having its outer uncovered portion formed into a hopper, a revoluble band-cutting and feeding cylinder disposed transversely over 65 said feed-pan, near the discharge of the hopper thereof, and under the cover of said frame, a power-shaft journaled in bearings on said frame, connections between said power-shaft and said band-cutting cylinder to drive the latter, eccentrics on said power-shaft and pitmen connecting said eccentrics to said feed-pan, substantially as described. 70 75

2. A band-cutting and feeding attachment for threshing-machines comprising a frame having means to detachably secure it to the feed end of a threshing-machine, an inclined reciprocating pan guided in a right line in and supported solely by said frame, the latter having a cover over the inner portion of 80 said feed-pan and said feed-pan having its outer uncovered portion formed into a hopper, a revoluble band-cutting and feeding cylinder disposed transversely over said feed-pan, near the discharge of the hopper thereof, and under the cover of said frame, a power-shaft journaled in bearings on said frame, 85 connections between said power-shaft and said band-cutting cylinder, to drive the latter and connections between said power-shaft and said feed-pan, whereby the latter is reciprocated, substantially as described. 90 95

In testimony whereof I have signed my name to this specification in the presence of two subscribing witnesses.

ISOM J. ROSS.
